UNITED STATES PATENT OFFICE.

HENRI FOCKÉ, OF VILLEMONBLE, AND FRÉDÉRIC MARIN, OF PANTIN, FRANCE.

PIANOFORTE.

Application filed April 19, 1923. Serial No. 633,258.

To all whom it may concern:

Be it known that we, HENRI FOCKÉ, a citizen of the French Republic, residing at 35 Avenue Gallieni, Villemonble, Seine, France, and FRÉDÉRIC MARIN, a citizen of the French Republic, residing at 2 Cite des Foyers, Pantin, Seine, France, have invented new and useful Improvements in Pianofortes, of which the following is the specification.

10 This invention has for its objects an improvement in the manufacture of pianos.

The piano forming the subject matter of the invention comprises, as other known pianos, a cast iron frame behind which the 15 sounding-board, provided with a wooden framing of small cross section, is secured for instance by means of screws passing through the said framing and screwing into the cast iron frame.

20 In the known pianos of this type, the pressure of the springs on the bridges has the effect of producing between the cast iron frame and the sounding-board a certain play or clearance, as the screws and the light 25 wooden frame cannot withstand the distortion of the sounding-board. When the wooden frame is of large cross section this is avoided, but the width of the piano is increased. Besides, whatever may be the cross 30 section of the wooden frame, the shrinkage of the wood owing to drying, produces some play in the assemblage.

The improvement forming the subject matter of the invention is adapted to produce a piano of the above mentioned type, in which the wooden frame, is of small dimensions but in which, however, the above 35 stated defects are overcome.

The invention consists in the arrangement 40 of an intermediate wooden member having an L-shaped cross-section, secured on the edge of the wooden frame of the sounding-board, and the front ledge of which fits over the ledge of the cast iron frame, this intermediate member being secured by screws on the cast iron frame and on the wooden frame and the side of the pianoforte being glued on this intermediate member.

The accompanying drawings illustrate, by 45 way of example, one form of carrying out this invention.

Fig. 1 is a rear elevation of a device in accordance with this invention.

Fig. 2 is a front elevation of the same.

50 Fig. 3 is a sectional plan view.

Fig. 4 is a plan view on an enlarged scale, parts being shown in section.

1 designates the side of the body of the piano, 2 the sounding-board, 3 the wooden framing of this sounding-board and 60 4 the cast-iron frame having a forwardly extending ledge and on which the sounding-board is removably secured by screws 10.

A wooden member 5 having an L-shaped cross-section is secured on the framing 3 and 65 on the plate 4 by screws 8 and 9.

This member is provided at its front part with a ledge 11 which bears against the front ledge of the plate 4 thus forming an abutment which securely and invariably 70 holds the cast-iron frame against the sounding-board 2.

Consequently, the pressure of the springs, which has a tendency to distort the sounding-board in the direction of the arrow 12, 75 cannot produce any play between the frame 4 and the table 2.

It is moreover to be noted that the assemblage thus effected tends to contract in proportion to the shrinkage of the wooden 80 member 5, as this contraction is always greater than that of the member 3, the member 5 being wider.

The side 1 of the body is glued on the member 5 and, for greater security, connected to the latter by screws 6 and 7 which respectively pass through the framing 3 and the ledge of the cast-iron frame 4.

The assemblage thus carried out forms a very homogeneous whole and indefinitely 90 preserves an absolute rigidity.

What we do claim as our invention and desire to secure by Letters Patent is:

1. In a piano, a sounding-board, a wooden frame placed on one side of the sounding-board, a cast-iron frame having a ledge and placed on the other side of the sounding-board, screws passing through the wooden frame and the sounding-board and screwing in the cast-iron frame, a wooden member having an L-shaped cross-section, an inner face of which covers the joints of the wooden frame, sounding-board and cast-iron frame and the other inner face of which 95 covers the ledge of the cast-iron frame, 100 means connecting the wooden member having an L-shaped cross-section to the wooden frame and cast-iron frame, and means for securing a side of the piano to the wooden member having an L-shaped cross-section. 105 110

2. In a piano, a sounding-board, a wooden frame placed on one side of the sounding-board, a cast-iron frame having a ledge and placed on the other side of the sounding-board, screws passing through the wooden frame and the sounding-board, and screwing in the cast-iron frame, a wooden member having an L-shaped cross-section an inner face of which covers the joints of the wooden frame, sounding-board and cast-iron frame and the other inner face of which covers the ledge of the cast-iron frame, screws passing through the wooden member having an L-shaped cross-section and screw-

ing in the wooden frame, screws passing through the wooden member having an L-shaped cross-section and screwing in the cast-iron frame, screws passing through the wooden frame and screwing in the member of L-shaped cross-section and in a side of the piano, and screws passing through the cast-iron frame and screwing in the member of L-shaped cross-section and in the said side of the pianoforte.

In testimony whereof we have signed our names to this specification.

HENRI FOCKÉ.

FRÉDÉRIC MARIN.
